INVENTOR
FREDERICK HAGHMANN
BY Edward G. Longman
ATTY.

UNITED STATES PATENT OFFICE.

FREDERICK HACHMANN, OF ST. LOUIS, MISSOURI, ASSIGNOR TO WILLIAM H. GREGG,
OF ST. LOUIS, MISSOURI.

METAL BOOK COVER.

Application filed March 12, 1921. Serial No. 451,930.

To all whom it may concern:

Be it known that I, FREDERICK HACHMANN, a citizen of the United States, and resident of the city of St. Louis and State 5 of Missouri, have invented certain new and useful Improvements in Metal Book Covers, of which the following is a specification containing a full, clear, and exact description, reference being had to the accompanying drawings, forming a part hereof.

My invention relates to improvements in metal book covers, and has for its object a book cover constructed entirely of metal, which is adapted to hold a sales ticket, a 10 tissue book and a total sales check.

In the drawings—

Fig. 1 is a side elevation of my device in closed position;

Fig. 2 is a top plan view of the same;

Fig. 3 is a view showing the book open, with one of the tissue sheets inserted beneath the sales slip;

Fig. 4 is a plan view of the book opened, with the sales ticket and tissue book removed;

Fig. 5 is a plan view of one of the covers, partially formed;

Fig. 6 is a similar view of the other cover, partially formed;

Fig. 7 is a plan view of the sales ticket carrying portion as stamped;

Fig. 8 is a plan view of the tissue book retaining means as stamped;

Fig. 9 is a perspective view of the same after being formed;

Fig. 10 is a plan view of the spring clip for holding the sales ticket in place as stamped; and

Fig. 11 is a fragmental perspective of one 40 of the covers showing the pocket for retaining one edge of the total sales ticket.

In the construction of my device I employ a book having covers 12 and 13. Both of these covers are provided adjacent three 45 edges with a bead 14, which is for the purpose of stiffening the covers and also to prevent their scratching the furniture.

The cover 12 is provided along one of its narrow edges with a projecting flange 15, and on the other with a series of slits forming the tongues 16 and 17. The tongues 16 are adapted to be formed into eyelets, while the tongues 17 are bent over on the inside of the cover to act as retaining means for the sales slip. The cover 12 is provided along

its side or along edges with flanges 18. These flanges are adapted to be folded over and act as stiffening ribs for the cover, as well as to close the ends of the pocket 19 formed by bending the flange 15. (See Fig. 11.)

The cover 13 is longer than the cover 12, and is provided along both of its short edges with projections 20 and 21, which are adapted to be bent into eyelets. The cover 13 is longer than the cover 12 and is provided with a right-angular bent portion 22, this forming the back of the book, the portion 22 being adjacent the tongues or projections 20.

In the portion 22 of the cover 13 are formed perforations 23, through which rivets 70 are designed to pass, these rivets passing through openings 24 formed in the portion 25 of the tissue book retaining means 26. This retaining means is stamped from a single sheet of metal and has one portion 75 thereof grooved as at 27. This is for the purpose of stiffening.

Adjacent the grooved portion 27 is a slit 28, extending almost the entire length, and the portion 27 is folded over the portion 25, as is clearly shown in Fig. 9. This tissue book retaining clamp is made of spring 80 metal and in order to insert the book the free portion 27 is pulled outward and one of the covers of the tissue book 29 inserted between the members 25 and 27. This securely holds the book in position.

The sales ticket supporting means consists of a leaf or plate 30, which is provided along one of its short edges with projections or 90 tongues 31, which are designed to be bent into the shape of eyelets and inserted between the eyelets formed out of the projections 21. After this insertion has been completed, a wire 32 is inserted through the eyelets, thus forming a hinge. The eyelets formed out of the projections or tongues 16 are inserted between the eyelets formed out of the projections 20 and a wire 33 inserted, which forms a hinge for the two covers. 95

The opposite short edge of the plate 30 is provided with projections 34, which are also formed into eyelets. The plate 30 has formed in it a series of serrations 35, which are designed to be bent upward at right angles, as illustrated in Fig. 1, and grip the under side of the sales ticket 36. The plate 30 is also provided with a vertical bent portion 37, this portion being adjacent the tongues 34.

The upper clamping member consists of a bar 38 having a serrated edge 39, which is designed to be bent at right angles and come in contact with the upper face of the sales book 36. The plate 38, is further provided on both its ends with projections 40, which extend beyond the edge of the book and are for the purpose of raising the plate 30 so that the used sheet from the tissue book can be readily inserted under the plate 30. The plate 39 is also provided with a thumb notch 41, for raising the plate when it is desired to insert the book.

Along the edges of the plate 38 and opposite the serrated edge 39 are projections 42, which are bent into the form of eyelets and inserted between the eyelets formed out of the projections 34. Through these eyelets is inserted a wire 43 which forms a hinge connection, and surrounding the hinge connection or wire 43 are the prongs 44, which place pressure on the plate 38 and hold the serrations 39 tightly against the sales ticket 36.

As illustrated in Fig. 4, the total sales ticket 45 is inserted in the pocket 19 and under the projections 17, thus securely holding the ticket in its proper position.

In using the sales book, the same is opened as shown in Fig. 3.

The uppermost sales ticket is raised and one leaf of the tissue book inserted underneath it and as the sales tickets are made out in duplicate with a double faced carbon, this carbon will make an impression on the tissue sheet at the same time that the duplicate sales tickets are being made out. Then, in order to place the tissue sheet underneath the plate 30, it is only necessary for the clerk to grip the projections 40 and raise the plate 30. This will withdraw the tissue sheet from between the sales tickets and when the plate 30 has been raised sufficiently the tissue sheet will fall of its own accord and rest on the cover 13, when the plate 30 can be lowered upon the tissue sheet.

Having fully described my invention, what I claim is:

1. A metal book cover, comprising a cover having a back formed integral therewith, eyelets formed on said back and one edge of the cover, a second cover having eyelets formed along one edge thereof, a wire inserted through said last mentioned eyelets and the eyelets formed on the back and adapted to form a hinge, a plate having eyelets along one edge, a wire adapted to be inserted through the eyelets on the first

mentioned cover and the plate for hingedly connecting the same together, upwardly projecting teeth formed integrally with said plate, an upward projection having eyelets formed integrally with said plate, a second plate having eyelets hingedly attached to the eyelets on the first mentioned plate, downwardly projecting teeth formed integrally with the said last mentioned plate, and a clamp formed of spring material secured to the back of the book, said clamp adapted to receive and hold a tissue book within the covers.

2. A device of the class described comprising a cover, a back integrally formed therewith, a second cover hingedly secured to said back, a spring clamp secured to the back for securing a tissue book thereto, a plate hingedly secured to the free end of the first mentioned cover, a clamp hingedly connected to said plate for securing a sales ticket book thereto, and projections formed integral with said clamp, said projections extending beyond the side edges of the cover.

3. A device of the class described comprising a cover, a back integrally formed therewith, eyelets formed on one edge of the cover and on said back, a second cover having eyelets formed along one edge thereof, a wire inserted through said last mentioned eyelets and the eyelets formed on the back and adapted to hingedly connect the cover and back, a pocket formed along the free edge of said cover, bent-over portions formed along the hinged edge of said cover, said pocket and bent-over portions adapted to hold a total sales ticket, a plate having eyelets along one edge, a wire adapted to be inserted through the eyelets on the first mentioned cover and the plate for hingedly securing the same together, an upwardly projecting portion having eyelets integrally formed with said plate, upwardly projecting teeth formed integral with said plate near the upturned portion, a second plate having eyelets and downwardly projecting teeth hingedly attached to the eyelets on the first mentioned plate, projections formed on each end of said second mentioned plate, said projections extending beyond the side edges of the cover and acting as a lifting means for said plate, and a clamp formed of spring material secured to the inside of the back of the book, said clamp adapted to receive and hold a tissue book within the cover.

In testimony whereof, I have signed my name to this specification.

FREDERICK HACHMANN.
